UNITED STATES PATENT OFFICE.

SIDNEY A. ROBINSON, OF KENT, WASHINGTON, ASSIGNOR TO CARNATION MILK PRODUCTS COMPANY, OF SEATTLE, WASHINGTON, A CORPORATION OF DELAWARE.

CAN-HEADING MACHINE.

Application filed May 9, 1923. Serial No. 637,919.

To all whom it may concern:

Be it known that I, SIDNEY A. ROBINSON, a citizen of the United States, and a resident of Kent, county of King, and State of Washington, have invented certain new and useful Improvements in Can-Heading Machines, of which the following is a description.

This invention relates to can heading machines and has for its principal object to provide electrically controlled means for holding and positioning a can head whereby it may be accurately assembled in connection with the end of the can body to be soldered or otherwise permanently fixed thereto.

In accomplishing the above purpose, in one embodiment of my present invention, I propose to equip can heading machines such as are now employed in this art with electro-magnets and with a suitably arranged automatic timing device for energizing the magnets and maintaining the respective magnets in energized condition for definite periods of time, each magnet by its attractive influence, holding and positioning a can end for application to the can body. I have found in practice that the use of electro-magnets enables me to so positively and accurately position the can ends with respect to the walls of the can bodies that possible leaks at the heads of the can may be obviated and also that the speed of operation of the heading machine can be materially increased.

With the above and other objects in view, the invention consists in the improved can heading machine and in the form, construction and relative arrangement of its several parts, as will be hereinafter described, illustrated in the accompanying drawings and subsequently incorporated in the subjoined claims.

In the drawings wherein I have disclosed the application of one practical and satisfactory embodiment of the present invention to the conventional type of can heading machines, and in which similar reference characters designate corresponding parts throughout the several views:

Figure 1 is a side elevation of the can heading machine having the present invention applied thereto;

Fig. 2 is a sectional view taken on the line 2—2 of Fig. 1;

55

Fig. 3 is a detail section through one of the can holding devices taken on the line 3—3 of Fig. 2;

Fig. 4 is an end elevation thereof;

Fig. 5 is a detail section taken on the line 5—5 of Fig. 4 illustrating the mounting of the can end holding magnet; and

Fig. 6 is a diagrammatic view illustrating the operating circuit for the electromagnets.

65

For purposes of illustration, I have shown a well known type of can heading machine wherein spaced rotary heads are fixed upon a common shaft 5. Each of these heads carries a circularly arranged series of can holding devices consisting of inner fixed jaw members 6 and outer radial slidable jaw members 7. The opposed faces of these jaw members are concaved to receive the end of a can body and at one end of the recess in the fixed jaw 6, a plate or disc 8 is suitably secured. This plate is provided with a central opening in which one end of the electromagnet 9 is mounted and secured in any approved manner. Preferably, the magnet is arranged to project through one side of the disc 8, and therefore, as shown in the drawings, the magnet may be conveniently secured in fixed relation to the disc by providing the magnet core at one of its ends with a flange 10 fitting into the rabbeted edge of the opening in the disc and fixedly secured therein by any approved means, as by brazing or up-setting the metal at the edge of the opening.

75

In the rotation of the heads, the sliding jaw members 7 are successively moved inwardly towards the fixed jaw members and retained in such position during a predetermined portion of each revolution by means of the spaced plunger members 11 suitably mounted upon the frame of the machine to engage the arms 12 of the movable jaw members. Such inward movement of the jaw members is retained and said members returned to their normal positions by means of suitable springs 13.

85

The energization of the electromagnets 9 is properly timed so that the corresponding magnets carried by the rotating heads will be energized only during the time required to fix the can heads to the can body. Since

100

105

the means for effecting a permanent connection between the ends of the can and the body constitute no part of my present invention, it is not herein described in detail. The timing mechanism for the electromagnets is diagrammatically illustrated in Figure 6 of the drawings. Between one of the bearings for the shaft 5 and one of the rotating heads, a member 14 of suitable insulating material is fixed upon said shaft and carries a plurality of circumferentially spaced contacts 15 projecting from the periphery thereof, said contacts corresponding in number with the number of magnets on each head. These contacts are adapted to successively engage the timer shoe 15' suitably fixed to the machine frame and insulated therefrom. In concentric relation to the member 14 a plurality of spaced metal segments 16 are mounted, each of said segments being connected by a wire 17 to one of the contacts 15. Wires 18 also connect these plates or segments 16 with the magnets 9 of the adjacent rotary head, the magnets of said head being electrically connected with the corresponding magnets of the other head by the wires 19, the opposite side of the magnet coil being connected to a part of the machine frame serving as a ground through the wires 20. Current is supplied through the timer shoe 15' from any suitable source, as diagrammatically shown in Figure 6, but preferably, I use a 110 volt direct current generator. Since only 90 volts and two amperes are required for the energization of the magnets, I interpose in the circuit as a resistance two 120 watt carbon lamps indicated at 21, which may also conveniently serve as pilot lights. However, it will be understood that a suitable resistance of any other type may be employed if desired.

It will be understood from the above that as the contacts 15 successively engage the timer shoe 15' the corresponding magnets are energized. The can body with the ends assembled are fed into the top of the machine as shown in Figure 2 of the drawings, and are received in the holding devices carried by the spaced heads as they successively reach a predetermined position. In the continued rotation of these heads, the outer holding jaws 7 are moved inwardly upon the can body and can ends and simultaneously the electromagnets 9 are energized. The magnetic attraction of these magnets upon the can heads serves to fixedly hold the latter in a perpendicular position. The length of the timer shoe 15' is such that the magnets remain energized for the period requisite to insure that the can ends will be properly drawn and held in applied position while they are being permanently fixed on the ends of the can body. Owing to the very positive action of the electro-

magnets and the accurate position of the can ends, header leaks in the completed cans are avoided and it is also possible to operate such a can heading machine at greater speeds than has heretofore been permissible. 70

From the foregoing description considered in connection with the accompanying drawings, the construction, manner of operation and several advantages of the invention will be fully and clearly understood. 75 It will be seen that I have, by means of a relatively simple attachment to can heading machines now generally employed in this art, produced an efficient, positively acting electrically controlled means for holding and accurately retaining the can ends in perpendicular position for proper application to the previously formed can bodies. In so far as I am aware such electrically controlled can end holding means is broadly new in the art, and it will, therefore be understood that while I have herein disclosed a specific embodiment of my present invention, in its practical application and use, it is not necessarily limited to the details of structure relative to the mounting of the electromagnets or the automatic timing means for the energization thereof. Therefore, I reserve the privilege of exemplifying my present improvements in other possible mechanical structures whereby the desired results may be secured and which may be fairly considered within the spirit and scope of the appended claims. 90

I claim.

1. In a can heading machine comprising a pair of spaced heads fixedly mounted on a rotary shaft, an inner series of can receiving jaws and outer series of relatively movable engaging jaws carried by each head in complementary relation with one another, means adjacent to said heads for feeding can bodies each having unsecured ends between the heads into each set of jaws as the shaft is rotated, means operative successively to hold each pair of unsecured can ends in perpendicular relation in the jaws at the end of the associated can body for a portion of the rotation of the shaft, and means simultaneously operating the jaw members during the assembling of the can ends on the can body, after which the can is released from the heads and the jaws are maintained in open position. 110

2. In a can heading machine comprising a pair of spaced heads fixedly mounted on a rotary shaft, an inner series of can receiving jaws and outer series of relatively movable engaging jaws carried by each head in complementary relation with one another, each head having a series of electromagnets associated with said jaws and a series of electric circuits therefor adapted to be individually and successively energized, means adjacent to said heads for feeding can 120

125

130

bodies each having unsecured ends between the heads into each set of jaws as the shaft is rotated, means operative to energize each cooperating pair of said electromagnets successively to hold each pair of unsecured can ends in perpendicular relation in the jaws at the end of the associated can body for a portion of the rotation of the shaft, and means simultaneously operating the jaw

members during the assembling of the can 10 ends on the can body, after which the can is released from the heads and the jaws are maintained in open position.

In testimony that I claim the foregoing as my invention, I have signed my name 15 hereunder.

S. A. ROBINSON.
